UNITED STATES PATENT OFFICE.

CHARLES D. KENNEDY, OF CALIFORNIA CITY, CALIFORNIA.

MACHINE FOR MAKING SHELLS.

SPECIFICATION forming part of Letters Patent No. 439,820, dated November 4, 1890.

Application filed June 24, 1890. Serial No. 356,548. (No model.)

To all whom it may concern:

Be it known that I, CHARLES D. KENNEDY, a citizen of the United States, residing at California City, Marin county, State of California, have invented an Improvement in Machines for Making Shells; and I hereby declare the following to be a full, clear, and exact description of the same.

My invention relates to the class of shell-making machines specially adapted for the making of paper shells in which material is packed—such as powder.

My invention consists in the novel constructions, combinations, and arrangements hereinafter fully described, and specifically pointed out in the claims.

The object of our invention is to provide a simple and effective machine which shall roll the sheet into cylindrical form, twist one end of the cylinder into a bottom for the shell, and remove and discharge the completed shell.

Referring to the accompanying drawings for a more complete explanation of my invention, Figure 1 is a side elevation of my machine. Fig. 2 is an end view. Fig. 3 is a vertical section of the twisting mechanism. Fig. 4 is a side elevation of the same. Fig. 5 is a perspective view of a completed shell.

A is the frame of the machine, having a top a. Mounted in a vertically-movable frame b, which is adapted to operate through the top of the frame, are horizontal parallel friction-roller B, of rubber or other suitable material. In bearings c on the top a is mounted a hollow or tubular shaft C, the end c' of which constitutes the former and projects directly over and parallel with the friction-rollers B. The operation of these parts is as follows: The friction-rollers B are raised up after the end of the sheet is fed to them, so as to bind said end between them and the former c'. The shaft C is rotated, whereby the former winds up the paper upon itself as many times as may be desirable to make the shell complete and stiff enough.

The vertical movement is given to the friction-rollers by the following mechanism: The lower end of the frame b rests upon a pivoted trip-bar b', having a cam b² on the underside of which the upper end of a pivoted gravity-lever b³ impinges. Mounted in the lower por-

tion of the frame is the drive-shaft D, having upon it a cam d, which is adapted to come in contact with the lower end of the lever b³. 55 When this contact occurs, as is shown in Fig. 2, the lever is vibrated, so that its upper end removes itself from the cam b² of the trip-bar b', thereby allowing said bar to drop down, and consequently the frame b and the rollers B, 60 which it carries, drop down. As soon as the cam d passes the lever b³ said lever swings back to a perpendicular by the weight of its lower end, whereby its upper end, coming again under the cam b², raises the swinging 65 trip-bar b', which raises the frame b and the friction-rollers B. A rotary motion is imparted to the former by means of a pulley c² on the shaft C, from which a belt c³ extends to a pulley d' on the drive-shaft D. 70

When the paper cylinder or shell is formed it is necessary to twist one end of it to make a bottom for the shell. This is effected by the mechanism which is shown in sectional detail in Fig. 3. Suitably secured by its bottom to a standard a', rising from the top a, is a ring E. Upon this ring and adapted to move upon it as an axis is a movable ring F. The inner or stationary ring has an opening e at one side, and the outer or movable 80 ring has a corresponding opening f in its side, and these openings admit the projecting end of the paper to the hollow center of the inner ring, as it winds up about the former, as here-tofore described. 85

Pivoted at g in the inner or stationary ring E are the twister-arms G, the outer ends of which pass into sockets in the movable ring F, and are freely slotted over pins therein, as shown at g'. The inner end of these twister-arms lie normally in seats in the inner ring, 90 as is shown in full lines in Fig. 3, and they then continue the contour of the inner surface of the ring, whereby in this position they do not interfere with the proper forming of the cylindrical shell. Now, it will be seen that if the outer or movable ring F be moved upon the inner or stationary ring E it will turn the twister-arms upon their pivotal centers, thereby throwing their inner ends directly to the center of the device, as is shown by the dotted lines in Fig. 3. As the projecting end of the paper shell lies within this center, these arms, when thus projected inward-

ly, catch the end of the paper, clamping it to a center and holding it there. Then the continued revolution of the shell on the former will twist the end of the paper into a closed bottom. This movement of the outer ring F is effected as follows: Secured to its lower portion by a suitable yoke h is a downwardly-extending arm H. Upon the power-shaft D is a cam d², which is adapted to come in contact with the lower end of the arm H, thereby pushing it over and turning the ring F. When released of the cam, the arm H returns to its vertical position, and the ring F, returning, withdraws the twister-arms into their seats. Now, in order to press this twisted bottom of the shell into shape, and also to remove the shell from the former and discharge it, I have the following mechanism. Passing through the hollow shaft C and the former c' is a push-rod I, the inner end i of which lies within the former, and is adapted to fit within the bottom of the shell. This rod is mounted so as to have a sliding longitudinal motion, and is provided with the spring J to return it to position. Mounted in suitable standards a² on the table-top is a slide-bar K, the end of which opposes the end i of the push-rod I. The push-rod I, when the twister-arms heretofore described have operated upon and formed the bottom of the shell, is projected so that the formed bottom of the shell is clamped between its end i and the opposing end of the slide-bar K, and is thereby pressed into shape. The push-rod I continues its movement, the slide-bar K yielding before it so that the entire shell clamped by its bottom between the push-rod and slide-bar is drawn off of the former c' over to the left until it is completely free of said former. This movement of the push-rod I is effected by means of a cord L, which is attached at its outer end to an arm i' of the push-rod, and thence passing over a suitable guide-pulley l has its lower end connected with a crank-pin m on a rotary disk M below. When the limit of this movement is reached and the disk M is released or tripped, as will presently be described, then the spring J rapidly returns the push-rod, withdrawing it from the shell, and when wholly withdrawn said shell drops down through an opening in the table-top. The slide-bar K now returns to its normal position by means of the cord N, which is secured at its upper end to an arm k of said slide-rod and at its lower end to the strap o of an eccentric O, mounted upon the power-shaft D. The outward movement of the slide-bar is due to the push of the rod I, but its return movement is due to the cord N.

The disk M is tripped by the following mechanism: Referring to Figs. 1 and 2, it will be seen that the disk is mounted freely upon the outer end of the shaft D, and is provided with a peripheral inwardly-extending flange m'. Securely fixed to the shaft D just within the disk M is a disk P, which carries in its rim a pivoted catch-bar p, the outer end of

which extends into a groove m² in the flange m' of the disk M. This groove at one portion, as is shown in Fig. 2, has a projection m³, which when the catch p comes in contact with it effects the engagement of the two disks, whereby the outer disk M is partially rotated. Upon the side of the table, as shown in Fig. 1, is a fixed trip-pin Q, and with this the inner end of the catch p is adapted to come in contact, whereby its outer end is released from the projection m³ in the groove m² of the disk M, thereby freeing said disk and allowing it to return under the power of the spring J, as heretofore described.

The general operation of the machine is therefore as follows: The end of the paper or other sheet from which the shell is to be made is first placed with its edge resting upon the friction-rollers B. These rollers are now raised so as to bind the sheet between themselves and the former c', and as said former rotates the sheet is wound into cylindrical form upon it. As soon as the cylinder is formed, the twister-arms twist its bottom into shape and immediately release it. Thereupon the push-rod I presses the bottom between its end i and the opposing end of the slide-bar K, and continuing this pressure the push-rod carries the entire shell off the former over to one side. As soon as it is free, the push-rod, which is slightly smaller than the inner diameter of the shell, springs back out of the shell, which thereupon drops down, and the slide-bar K returns to its normal position.

Although I have here spoken of the former c' as being the end of the shaft C, it is evident that for different sizes of cylinders I may slip suitably-sized tubes upon said end, and they would thus become the formers.

Having thus described my invention, what I claim as new, and desire to secure by Letters Patent, is—

1. In a machine for making shells, the combination of the rotating former, the friction-rolls B below said former, and the means for raising and lowering said rolls, consisting of the vertically-movable frame in which they are mounted, the swinging trip-bars sustaining the lower end of the frame and having a cam b², the pivoted gravity-lever b³, having its upper end operating under the cam b², the rotary shaft D, and its contact-cam d for vibrating the lever, substantially as herein described.

2. In a machine for making shells, the combination of the hollow or tubular rotary former, the sliding push-rod operating through said former, and the opposing slide-bar opposite the end of the push-rod, whereby the shell is removed from the former and discharged, substantially as herein described.

3. In a machine for making shells, the rotary former about which the sheet is wound, and twister-arms for twisting one end of the shell to form its bottom, substantially as herein described.

4. In a machine for making shells, the com-

bination of the hollow or tubular rotary former, the sliding push-rod operating through said former, and twister-arms at the end of the shell for twisting one end thereof and 5 forming the bottom, substantially as herein described.

5. In a machine for making shells, the combination of the tubular rotary former, twister-arms for twisting one end of the shell and 10 forming its bottom, the sliding push-rod operating through the former against the inner surface of the bottom of the shell, and the opposing sliding bar K, operating against the outer surface of the bottom of the shell, substantially as herein described.

6. In a machine for making shells, the device for twisting the end thereof to form the bottom, consisting of the inner fixed ring, the outer movable ring, and the twister-arms pivoted to and seated in the inner ring and having their outer ends pivoted in the movable ring, substantially as herein described.

7. In a machine for making shells, the device for twisting one end thereof to form its bottom, consisting of the inner or fixed ring E, having an opening at one side, the outer movable ring F, having a corresponding opening to admit the end of the shell to the hollow center of the inner ring, and the twister-arms 25 pivoted and seated in the inner ring and having their outer ends pivoted in the movable ring, substantially as herein described.

8. In a machine for making shells, the device for twisting the end of the shell and 35 forming its bottom, consisting of the fixed inner ring, the movable outer ring, the twister-arms pivoted in the inner ring and having their outer ends pivoted to the outer ring, the downwardly-extending arm of the outer ring, 40 the rotary drive-shaft, and the contact-cam of said shaft operating against the arm whereby the outer ring is moved, substantially as herein described.

9. In a machine for making shells, the combination of the rotary former about which the 45 sheet is wound to form the shell, and the device for twisting the end of the shell to form its bottom, consisting of the inner fixed ring E, having a side opening, the outer movable ring F, having a corresponding side opening,

and the twister-arms pivoted to and seated in the inner ring and having their outer ends pivoted in the outer ring, substantially as herein described.

10. In a machine for making shells, the combination of the tubular rotary former, a push-rod operating through said former, the opposing slide-rod, and the device for twisting the end of the shell, consisting of the inner fixed ring having a side opening, the outer 60 movable ring with a corresponding side opening, and the twister-arms pivoted in the inner ring and having their outer ends pivoted in the outer ring, substantially as herein described. 55

11. In a machine for making shells, the tubular former, in combination with the sliding push-rod operating through said former, and the means for operating the push-rod, consisting of the cord L, secured to it, the rotary disk M, having a crank connected with the cord, the inner disk P, having a catch engaging the disk M, the trip-pin Q, for releasing the catch, and the spring J, for returning the rod, substantially as herein described. 65

12. In a machine for making shells, the tubular rotary former, in combination with the reciprocating push-rod operating through it, the opposing slide-bar K, and the means for returning the slide-bar, consisting of the cord 8c N, the eccentric O, the power-shaft D, and eccentric-strap o, substantially as herein described. 75

13. A machine for making shells, comprising a tubular rotary former, vertically-movable friction-rollers under said former, a reciprocating push-rod operating through the former, twister-arms at one end of the shell for forming its bottom, and a slide-bar between which and the end of the push-rod the 9c bottom of the shell is clamped and said shell removed from the former and discharged, substantially as herein described. 85

In witness whereof I have hereunto set my hand.

CHARLES D. KENNEDY.
